HEAT-TREATING MECHANISM FOR COIL SPRINGS

Martin J. Nelson and Edward Turecki, Chicago,
Ill., assignors to Wunderlich Spring Machinery
Company, a corporation of Illinois

Application August 8, 1952, Serial No. 303,378

9 Claims. (Cl. 219—11)

1

This invention relates to a heater mechanism for heat treating coil springs and is an improvement over the heater mechanism disclosed in copending application Serial No. 235,154, filed July 5, 1951, by Martin J. Nelson and Clifford E. Ives. The heater mechanism of this invention, while of general utility, is particularly adaptable for use with a coil spring producing machine, such as disclosed in application Serial No. 700,197, filed by William E. Wunderlich on September 30, 1946, now Patent No. 2,604,202 of July 22, 1952, for individually heat treating the coil springs as they are formed by the machine.

The principal object of this invention is to provide an improved heater mechanism for heat treating coil springs wherein the end turns of the coil springs are securely clamped and electrically contacted for passing electrical current therethrough, thereby eliminating arcing and providing uniform heat treating throughout the length of the coil spring, wherein electrical current is applied to the coil spring only when the end turns thereof are securely clamped and electrically contacted, wherein the interval of time during which electrical current is applied may be readily adjusted for obtaining the desired heat treatment of the coil springs, wherein the application of electrical current to and the clamping and electrically contacting of the coil springs are positively and mechanically synchronized for foolproof operation, wherein the heater mechanism may be readily adjusted for accommodating coil springs having different lengths, diameters, wire gauge and the like, wherein the heater mechanism may be readily applied to coil spring producing machines for synchronous operation therewith, and wherein the heater mechanism is simple in construction, foolproof in operation and inexpensive to manufacture. The heater mechanism of this invention differs essentially from that of the aforementioned Martin J. Nelson and Clifford E. Ives copending application in the construction of and the manner of operation of the clamping members for clamping and electrically contacting the end turns of the coil springs being heat treated.

Briefly, the heater mechanism of this invention includes an elongated supporting base and a shaft extending along the elongated supporting base and rotatably mounted thereon. Two spaced pairs of clamping members are provided for clamping and electrically contacting respectively the end turns of the coil spring and preferably these two pairs of clamping members are longitudinally adjustably secured to the support-

2

ing base and encompass the shaft. Each pair of clamping members includes a normally stationary clamping member secured to the supporting base and a movable clamping member pivotally mounted on the normally stationary clamping member. Spring means urge the movable clamping members away from the stationary clamping members. A cam for each pair of clamping members is carried by the shaft and a cam follower on each movable clamping member engages its associated cam for moving the movable clamping members toward the stationary clamping members against the action of the spring means. A strain release connection is preferably provided between each cam follower and its movable clamping member. Means are provided for applying electrical energy to the clamping members electrically to heat treat the springs clamped thereby. Control means including switch means and cam means operated by the rotatable shaft apply electrical energy to the clamping members and hence to the coil spring only when the coil spring is securely clamped and electrically contacted by the clamping members. The control means is adjustable to regulate the time interval during which electrical energy is applied to the clamped coil springs. The rotatable cam shaft may be driven in synchronism with a coil spring producing machine for heat treating the coil springs as they are fabricated. The positions of the rotatable cam shaft and the various clamping members and cams operated thereby may be adjusted to accommodate coil springs of different lengths, diameters, wire gauges and the like.

Further objects of this invention reside in the details of construction of the heater mechanism and the cooperative relationships between the component parts thereof.

Other objects and advantages of this invention will become apparent to those skilled in the art upon reference to the accompanying specification, claims and drawings, in which:

Fig. 1 is a diagrammatic illustration of a coil spring producing machine of the type disclosed in the aforementioned William E. Wunderlich application, with the heat treating mechanism of this invention applied thereto.

Figs. 2 and 3 are perspective views of the coil spring which may be heat treated by the heat treating mechanism of this invention, Fig. 2 illustrating the spring before heat treating and Fig. 3 illustrating the spring after heat treating;

Fig. 4 is a wiring diagram of the means for ap-

plying electrical energy to the coil springs being heat treated and the control means therefor;

Fig. 5 is a front elevational view partly in section of the heat treating mechanism of this invention, illustrating the clamping members separated for receiving a coil spring;

Fig. 6 is a top plan view of the heat treating mechanism illustrated in Fig. 5;

Fig. 7 is an enlarged vertical sectional view through a portion of the heat treating mechanism and taken substantially along the line 7—7 of Fig. 6;

Fig. 8 is a partial sectional view corresponding to the right hand portion of Fig. 7 but illustrating a coil spring clamped by the clamping members for heat treating the coil spring;

Fig. 9 is an end elevational view looking from the left of Figs. 5 and 6;

Fig. 10 is a vertical sectional view taken substantially along the line 10—10 of Fig. 7;

Fig. 11 is a vertical sectional view taken substantially along the line 11—11 of Fig. 7;

Fig. 12 is a view illustrating the position of the left end of the coil spring as illustrated in Fig. 5 as it is clamped by the left hand clamping members;

Fig. 13 is a view similar to Fig. 12 but illustrating the position of and the manner in which the right end of the coil spring as illustrated in Fig. 5 is clamped by the right hand clamping members;

Fig. 14 is an exploded perspective view of the left hand clamping members;

Fig. 15 is an enlarged sectional view through the electrode portion of the left hand clamping members;

Fig. 16 is an exploded perspective view of the parts forming the electrode portions of the left hand clamping members.

Referring first to Figs 2 and 3, a coil spring to be heat treated is generally designated at 10. It includes a plurality of inner convolutions or turns 11, and a pair of end turns 12 terminating in knots 13. The coil spring may be plain as illustrated or the ends thereof may be clamped or offset, as desired. When the coil spring is originally fabricated, the knots 13 are located out of line as illustrated in Fig. 2, so that when the coil spring is heat treated the knots 13 line up as illustrated in Fig. 3, the heat treating of the coil spring causing a twisting within the coil spring.

Any suitable machine may be utilized for the purpose of fabricating the coil spring 10 and for purposes of illustration in this application Fig. 1 discloses a coil spring producing machine generally designated at 15 which may be of the type disclosed in the aforementioned William E. Wunderlich application. The machine 15 includes a base or standard 16 and a coiling mechanism 17 for coiling wire into the double ended coil spring 10. When the coil spring 10 is thus formed it is grasped by fingers 18 carried by radial arms 19 of a transfer mechanism 20 which is intermittently rotated in a counterclockwise direction as illustrated in Fig. 1. The coil springs 10 thus formed and grasped by the fingers 18 are advanced to a knotting mechanism 21 wherein one end of the coil spring 10 is knotted as at 13 and, if desired, crimped into an offset. The coil springs 10 are then advanced to a second knotting mechanism 22 wherein the other end of the coil spring is knotted and may also be crimped into an offset if so desired. The knotted coil springs 10 are then advanced by the

transfer mechanism to the heat treating mechanism of this invention, generally designated at 23. After the coil springs 10 are heat treated they are advanced by the transfer mechanism to a stacker mechanism 24 wherein the heat treated coil springs are stacked in nested form. Since the coil spring producing machine diagrammatically illustrated in Fig. 1 is fully disclosed in the aforementioned William E. Wunderlich application a further description thereof is not considered necessary.

The heat treating mechanism 23 of this invention includes an elongated supporting base 26 in the form of an angle member which is secured to the standard or support 16 of the coil spring producing machine by means of bolts 27. The upwardly extending leg of the supporting base 26 is provided adjacent its ends with a pair of vertically arranged slots 28. A pair of bearing blocks 29 and 30 are vertically adjustably secured to the supporting base 26 by screws 31 extending through the slots 28. A rotatable cam shaft 32 is rotatably journaled by bearings 33 and 34 in the bearing blocks 29 and 30 respectively, the shaft 32 extending longitudinally along the supporting base 26. By reason of the vertical slots 28, the bearing blocks 29 and 30 and hence the cam shaft 32 may be vertically adjustably positioned as desired. A bar 37 extending along the shaft 32 is secured to the bottoms of the bearing blocks 29 and 30 by means of bolts 38. This bar 37 is located forwardly of the supporting base 26 and is provided with a longitudinally arranged slot 39.

The shaft 32 is maintained in proper longitudinal position by means of collars 41 and 42 secured to the shaft 32 on opposite sides of the bearing block 30. The end of the shaft 32 carries a flanged hub 43 which is secured to the shaft by means of a key 44 and set screw. A gear 45 is secured to the flange of the hub 43 by screws 46. The gear 45 meshes with a driving gear 47 secured to a shaft 48 which drives the knotting mechanism 22. The shaft 48 makes one complete revolution in its operation of the knotting mechanism 22 and this is done during each cycle of operation of the coil spring producing machine. The gear 45 is preferably twice the size of the driving gear 47 so that during each cycle of operation of the coil spring producing machine 15 the rotatable shaft 32 of the heater mechanism is driven through one-half a revolution.

The heater mechanism of this invention includes a pair of clamping members, each pair including a stationary clamping member 50 having a slide portion 51 resting on the longitudinal bar 37. Projections 53 extend downwardly from the slide portion 51 on either side of the bar 37 for maintaining alignment thereof. A screw 54 extends through the slot 39 in the bar 37 for adjustably securing the stationary clamping member 50 in proper position on the bar 37. The stationary clamping member 50 is provided with a hole 55 for encompassing the shaft 32 and with a slot 56 extending downwardly from the hole 55. It is also provided with a transverse bore 57 communicating with the slot 56. The slot 56 is provided for the purpose of receiving and mounting a movable clamping member 58 having an extension 60 extending through the slot 56. The movable clamping member 58 is provided with a hole 61 for encompassing the shaft 32. The extension 60 is provided with a transverse bore 62 for receiving a pivot pin 63.

for pivotally mounting the movable clamping member 59 to the stationary clamping member 50. The stationary clamping member 50 and the movable clamping member 59 are each provided with a pair of sockets 64 and 65 respectively for receiving a pair of compression springs 66, the compression springs urging the movable and stationary clamping members apart as illustrated in Figs. 5 to 7. The clamping members are moved toward each other against the action of the 10 springs 66 to clamp the end turns 12 of the coil springs therebetween as illustrated in Fig. 3.

The extension 60 of the movable clamping member 59 is hollowed out at 68 and is provided at its end with a bore 69. It is also provided with an opening 70 in the bottom thereof. A cam follower member 71 having a bore 72 therein is pivotally mounted in the hollowed portion 68 of the extension 60 by means of a pivot pin 73 extending through the bores 69 and 72. A cam follower 74, preferably of the antifriction type, is secured to the end of the cam follower member 71 by means of a screw 75. The cam follower member 71 carries a stud 76 which extends downwardly through the opening 70 and which carries at its lower end nuts 77. A spring 78 is interposed between the extension 60 and the nuts 77 for urging the cam follower 74 upwardly. The amount of upward movement of the cam follower 74 with respect to the extension 60 is limited by a stop screw 79 carried by the extension 60 and locked in place by a lock nut 80. The spring 78 and the stop screw 79 operate to position the cam follower 74 with respect to the extension 60 of the movable clamping member and also to provide a strain release connection therebetween.

A pair of cams 81 is secured to the shaft 32 for engaging the cam followers 74 for operating the movable clamping members 59 against the action of the springs 66. These cams 81 are keyed to the shaft 32 by means of keys 83 located in key slots 82. The key slots 82 are elongated so that the cams 81 may be adjustably positioned along the shaft 32 and the cams 81 may be locked in desired adjusted position by means of set screws 84. The cams 81 operate pivotally to move the movable clamping members 59 towards the stationary clamping members 50 to provide a positive clamping action on the end turns 12 of the coil springs 10 and the extent of the clamping action may be regulated by adjusting the nuts 77 on the stud 76. If a coil spring should be improperly inserted between the stationary and movable clamping members, as for example, the knot 13 being interposed between the clamping members, then the spring 78 is compressed to allow pivotal movement of the cam follower member 71 with respect to the movable clamping member 59 to provide an effective strain release connection and to prevent breakage of the apparatus under these conditions. The cams 81 are preferably double cams and are rotated through 180 degrees during each cycle of operation of the coil spring forming machine 15. When the clamping members are adjusted along the supporting base 26 for accommodating coil springs of different length, the cams 81 are correspondingly adjusted along the shaft 32. This provides for simple adjustment of the heat treating mechanism for various length coil springs.

Referring more particularly to Figs. 14 to 16, the upper ends of the clamping members 50 and 59 are provided with transverse recesses 88 and 89 and holes 90 and 91 respectively. These are 75

utilized for the purpose of securing in place the electrodes for electrically contacting the clamped coil springs. The recess 88 of the stationary clamping member 50 receives an angular electrical insulating member 92 which is provided with holes 93 and a flared extension. In turn, the angular electrical insulating member 92 receives an angular electrical metallic wear plate 94 which in turn receives an angular electrical insulating member 95 having holes 96. This angular electrical insulating member 95 receives an electrode 97 having tapped holes 98 and a flared extension 99. One end of a metallic strap 100 is secured along with an electrical terminal 101 to the electrode 97 by means of a screw 102. In a like manner, the recess 89 of the movable clamping member 59 receives an angular electrical insulating member 103 having holes 104, an angular metallic wear plate 105, an angular electrical insulating member 106 having holes 107 and an electrode 108 having tapped holes 109 and a flared extension 110. Here the other end of the strap 100 is secured to the electrode 108 by means of a screw 111. The parts 92, 94, 95, and 97 are secured to the stationary clamping member 50 by means of a pair of screws 113 which are insulated from the clamping member 50 by means of an electrical insulating sleeve 112. In a like manner the parts 103, 105, 106 and 108 are secured to the movable clamping member 59 by a pair of screws 115 which in turn are insulated from the movable clamping member 59 by means of insulating sleeves 114. Thus, when the end turns of the coil springs are 30 clamped between the stationary and movable clamping members, they are firmly electrically contacted by the electrodes 97 and 108 for the purpose of passing electric current there-through for heat treating the same, the electric current being applied to the electrodes 97 and 108 through the electrical terminals 101 and the metallic straps 100. The metallic wear plates 94 and 105 and their associated insulating members 95 and 106 prevent electrical contact with the intermediate turns 11 of the coil springs and also operate to prevent wear of the electrical insulating members. Since in the operation of the heat treating mechanism of this invention the inner convolutions 11 of the coil springs might engage the electrodes at only one point as illustrated more clearly in Figs. 5, 7, 8, 12 and 13, only one of the electrodes need be provided with the overlying electrical insulating members and metallic wear plates. However, for uniformity all of the electrodes may be provided with this protective arrangement if desired. The flared ends 99 and 110 of the electrodes 97 and 108 are for the purpose of facilitating the insertion of the end turns 12 of the coil springs between the two pairs of clamping members 50 and 59.

A spacer block 120 is secured to the inside of the bearing block 29 and it has secured thereto by means of screws 122 a normally open switch 121 which is provided with a cam follower 123. A cam 124 having a pair of lobes 125 is secured to the shaft 32 by means of a set screw 126. As the shaft 32 is rotated the lobes 125 of the cam 124 operate the cam follower 123 for momentarily closing the normally open switch 121. The cam 124 is so positioned on the cam shaft 32 that the switch 121 is momentarily closed only after the clamping members 50 and 59 have securely clamped the end turns 12 of the coil to be heat treated.

A plate 128 is rotatably mounted on the shaft bearing 33 on the outside of the bearing block 29. An outer plate 129 is secured at its lower end through a spacer 130 and screws 131 to the lower end of the plate 128. A handle 132 is carried by a stem 133 which in turn is welded to the plate 129 for rotating the plates 128 and 129 about the shaft 32. The upper end of the plate 128 is provided with a slot 134 for receiving a screw 135 for adjustably locking the plate 128 in any desired rotative position. The upper end of the plate 128 may also be provided with suitable indicia 136 for indicating the rotative position of the plate. A normally closed switch 137 is secured to the plate 128 by screws 138 and it is provided with a cam follower 139 engaging a cam 140 having high lobes 141, the cam 140 being secured to the shaft 32 by a set screw 142. When one or the other of the lobes 141 of the cam 140 engages the cam follower 139, the switch 137 is momentarily opened. By moving the handle 132, the plate 128 and the switch 137 are correspondingly moved about the axis of the cam shaft 32 so that the switch 137 may be momentarily opened at various points in the rotation of the cam shaft 32, depending upon the adjustment of the switch carrying plate 123. Thus, the time at which the switch 137 is momentarily opened with respect to the time at which the switch 121 is momentarily closed may be adjusted at will by manipulation of the handle 132.

Electrical energy is applied to the electrodes 97 and 108 of the clamping members 50 and 59 and hence to the coil spring clamped thereby by means of a low voltage high current transformer which is designated generally at 150 in Fig. 4. This transformer is of conventional construction and has a primary 151 and a secondary 152, the secondary 152 being connected by suitable leads 153 to the electrical connectors 101 carried by the electrodes 97. Electrical energy is supplied to the primary 151 of the transformer by means of conductors 154 and 155 leading from some source of power not shown. The application of electrical energy to the primary 151 of the transformer 150 is controlled by a relay having an operating coil 156 for operating switches 157, 158 and 159. When the relay coil 156 is energized, the switches 157, 158 and 159 are closed and when the relay coil 156 is deenergized these switches are opened. The switches 157 and 158 control the application of electrical energy to the transformer primary 151, so that when the relay is energized electrical energy is applied to the transformer and when it is deenergized the application of electrical energy is interrupted. The switch 159 of the relay operates to complete a maintaining circuit for the relay.

The relay winding 156 is controlled by the normally opened switch 121 and the normally closed switch 137 operated by the cam shaft 32. It may also be controlled by a switch 161 and a start and stop switch 162. The switches 161, 162, 137 and 121 are connected in series with the relay coil 156 and the relay switch 159 is connected in shunt with the normally open switch 121. In order to energize the relay coil 156, the switches 161, 162, 137 and 121 must be closed and the relay may be maintained energized through the switches 161, 162, 137 and 159 independently of the switch 121 until switch 137 or switches 161 and 162 are opened.

Assuming that the switches 161 and 162 are 75

closed and that the coil spring producing machine is in operation with a coil spring to be heat treated moved between the clamping members 50 and 59 and securely clamped therebetween, the normally opened switch 121 is thereafter closed to complete a circuit from the conductor 155 through switches 161, 162, 137, 121 and relay coil 156 to the conductor 154. This energizes the relay coil 156 for closing the switches 157, 158 and 159. Closure of the switches 157 and 158 applies electrical energy to the transformer 150 and hence causes electrical current to course the coil spring 10 for heat treating the same. Closure of the switch 159 upon energization of the relay coil 156 completes a maintaining circuit for the relay coil 156 independent of the switch 121 so that when the switch 121 opens after being momentarily closed, the relay coil 156 remains energized. Upon further rotation of the cam shaft 32, the normally closed switch 137 is opened at a point in the cycle depending upon the adjustment of the switch with respect to the cam shaft 32. Upon opening of this switch 137, the maintaining circuit to the relay coil 156 is broken and the relay becomes deenergized for opening the switches 157, 158, and 159. Opening of the switches 157 and 158 interrupts the application of electrical energy to the coil spring 10 being heat treated. Opening of the switch 159 of the relay prevents the relay from again being energized until such time as the normally opened switch 121 is closed during the next cycle of operation. Thus, electrical energy is applied to each coil spring clamped between the clamping members 50 and 59 and the interval of time at which the electrical energy is so applied is dependent upon the adjustment of the normally closed switch 137. In all instances, electrical energy is applied to the electrodes 97 and 108 only when the end turns 12 of the coil spring are securely clamped by the clamping members 50 and 59. By adjusting the normally closed switch 137, the amount of heat treatment applied to each coil spring may be regulated at will.

An indicating lamp 163 may be connected across the conductors 154 and 155 to indicate that the heat treating mechanism is in condition for operation and an indicating lamp 164 may be connected across the primary 151 of the transformer 150 for indicating the period of application of electrical energy to the coil spring being heat treated.

The switch 161 in series with the relay coil 156 is operated by the clutch mechanism of the coil spring producing machine 15, so that the relay may be energized and electrical energy applied to the electrodes of the clamping members only when the coil spring producing machine is in operation. This effectively automatically prevents application of electrical energy to a coil spring when the coil spring producing machine is shut down. The start and stop switch 162 is conveniently located on the coil spring producing machine 15 so that the application of electrical energy through the electrodes of the heat treating mechanism may be interrupted at the will of the machine operator.

While for purposes of illustration one form of this invention has been disclosed, other forms thereof may become apparent to those skilled in the art upon reference to this disclosure and, therefore, this invention is to be limited only by the scope of the appended claims.

We claim as our invention:

1. A heater mechanism for heat treating coil

11

on each movable clamping member and engaging its associated cam for moving the movable clamping members toward the stationary clamping members against the action of the spring means.

9. A heater mechanism for heat treating coil springs comprising, an elongated supporting base, a shaft extending along the elongated supporting base and rotatably mounted thereon, two spaced pairs of clamping members for clamping and electrically contacting respectively the end turns of a coil spring, each pair of clamping members including a normally stationary clamping member encompassing the shaft and longitudinally adjustably secured to the supporting base and a movable clamping member encompassing the 15 shaft and pivotally mounted on the normally stationary clamping member, spring means for urg-

12

ing each movable clamping member away from its stationary clamping member, a cam for each pair of clamping members carried and rotated by the shaft, a cam follower on each movable clamping member and engaging its associated cam for moving the movable clamping members toward the stationary clamping members against the action of the spring means, and a strain release connection between each cam follower and its movable clamping member.
